SPRING WINDER

Leonard R. Buczkoski, Detroit, Mich.

Application February 10, 1944, Serial No. 522,195

3 Claims. (Cl. 153—67)

The purpose of my invention is to provide a practical and sturdy device for making coil springs out of wire, even when the wire out of which the springs are to be made is of a relatively large diameter such as would exceed the capacity of conventional hand operated devices for making springs.

Another purpose of my improvement is to provide a device capable of easy and quick adjustment to the pitch of the spring to be formed and to the diameter of the wire employed in forming said spring.

I shall now describe my improvement with reference to the accompanying drawings in which,

Fig. 1 is a side elevation of my spring winder, including a supporting member which is shown partly broken off;

Fig. 2 is a plan view of my spring winder without a wire feeder which is a part of said winder;

Fig. 3 is a sectional view of a detail of construction taken on line 3—3 of Fig. 1;

Fig. 4 is a front elevation of my spring winder;

Fig. 5 is a reduced perspective view of the winder with a mandrel and a partly wound spring thereon;

Fig. 6 is a sectional view on line 6—6 of Fig. 2;

Fig. 7 is a sectional view on line 7—7 of Fig. 2;

Fig. 8 is a perspective view of the wire feeder, forming a part of my winder.

Similar numerals refer to similar parts throughout the several views.

My winder includes a horizontal base 10 on an upright supporting column 11. At one end, which shall be designated as the front end, a plate 12 is affixed to base 10 by means of screws 13, the plate being set at an angle into a V-shaped formation with said base. In its upper portion the plate contains a rectangular window 14 the purpose of which will be described below. Disposed on the surface of base 10, in a sliding relation thereto and parallel to its longer side, is a bar 15, ending in a butt 16, having a flat face at right angle to base 10. The butt is of a size to enter into window 14. A guide 17, having an inverted groove 18, fits over the top of bar 15 and is secured to base 10 by means of a threaded bolt 19, the head of which rests on a washer 20. Pins 21, shown in Fig. 2, being in a sliding engagement with corresponding holes in guide 17, serve to keep said guide in proper alignment with the sides of base 10.

To effect a longitudinal adjustment of bar 15, I have provided a cross link 41 having axial end pins 43 and 49, said pins being seated in sockets in side plate 24 and bar 15, respectively. A han-

dle 50, having a shank 51, is hingedly connected by means of said shank to link 41.

Attached to one side of base 10 is a stud 22, held in place by screws 23. The stud serves as a support for a sliding side plate 24, having a slot 25 extending in the direction of the longitudinal axis of said plate. As said stud is disposed within the slot, the arrangement makes it possible to adjust the relative position of the plate with respect to the length of the base. A screw 26 passing through the slot into the side of base 10 serves as a means of holding the plate in a selected position.

Affixed to the front of the side plate 24, by means of a connecting member 27, is a head 28 in a sliding engagement with the connecting member 27 by means of a slot 29 cut in said member, a pin 30, projecting into the slot from the side of head 28, and a bolt 31, having its head outside the slot and being screwed into said head 28. The arrangement permits the head to be adjusted vertically to a desired height and to be retained at said height by means of said bolt 31. The connecting member 27 is secured to plate 24 by means of screws 32.

The front surface of head 28 is flat, set at right angle to base 10, and is cut off diagonally, as best shown in Fig. 4. A component part of head 28 is a spacer 33, having the shape of an angle bar with its front side cut to form a wedge 34. The face of the wedge projects beyond the front surface of head 28. The extent of said projection may be controlled by a pair of screws 35 within slots 36 in side of head 28. A coiled spring 37, shown in Fig. 2, bears against the wedge from inside urging it outwardly.

A component part of my spring winder is a removable feeder shown in Fig. 8. It consists of an elongated bar 38 and a clamp 43. The bar contains a groove 39 extending along its whole length to a tapered end 40. Pins 41 and 42, set beside the groove, are intended to prevent the wire to be used in making springs from buckling out of the groove. The clamp, as will be noticed, is U-shaped, one of its legs, 44, being affixed to bar 38, and the other, 45, having a screw 46 for a frictional engagement with the outer surface of side plate 24. The whole feeder, as clamped in position is shown in Figs. 1 and 5.

Two other component parts of conventional design are intended to be used with my spring winder. One of them is a clamp 53 and the other is a mandrel 52. The latter may be of any suitable diameter, depending upon the desired diameter of the spring to be made. The clamp 53,

best shown in Fig. 1, consists of a flat substantially rectangular unit with a central opening 54, circular in shape except for a V-shaped recess 55 for the reception of said mandrel. The mandrel is kept in place in said recess by means of a diagonal set screw 56. A jaw 57, controlled by a screw 58, serves to grip the free end of the wire to be wound on said mandrel. A rod 60 fitted into said clamp 53, serves as a lever for rotating the mandrel around its axis.

To complete the description of my winder, I wish to add that the base 10 is provided with a groove 59, along its inner edge, for a purpose which will be presently described.

I shall now describe the operation of my winder. First a mandrel of suitable diameter is set in place as shown in Fig. 5. Bar 15 is rammed against the mandrel by means of handle 50, and the bar is retained in place against movement by means of bolt 19. Next a wire of suitable diameter is led through groove 39 in the feed bar 38 towards the mandrel and the free end of it is affixed to the outside surface of clamp 53 by means of jaw 57. Side plate 24 is slidily brought forward towards the mandrel till the wedge shaped face 34 of spacer 33 is in contact therewith. Head 28, including the spacer, is then vertically adjusted depending upon the desired pitch of the spring to be made. It will be seen that the higher the spacer is raised, the closer to each other will be the individual coils of the spring. The free end of the wire which is to be made into a spring, is manually drawn out of the feeder and is affixed to clamp 53 by means of jaw 57, controlled by screw 58. The wire, leaving the feeder, passes to one side of the wedge-shaped spacer 34, being interposed between the angular plate 12 and said spacer 34. What now is necessary is now to rotate the mandrel around its axis by means of clamp 53. As the mandrel is rotated, the wire is wound around the mandrel, the first coil of the spring beginning at the outer end of the feeder, going over the top of the mandrel, continuing over the surface of the mandrel on the far side of the face of the spacer and completing the turn on the side of the spacer remote from angular plate 12. As the mandrel is continued to be rotated, one coil after another is being formed in this manner, the coils being separated by a distance equal to the width of the face of the spacer in contact with the mandrel. The mandrel, as above stated, is held in place within the V-shaped space between the angle plate 12 and base 10 of my device, but it is held there loose enough to permit the longitudinal movement of the mandrel, that is, the movement in the direction of the axis, the rate of the movement being regulated automatically by the pitch of the spring formed, as above stated. For the purpose of the movement of the mandrel, the

5 coils of the spring may be considered integral therewith, so that the mandrel and the coil forms a kind of a worm in operative engagement with my said spacer. A spring 61, on mandrel 52, as made from wire 62, is shown in Fig. 2.

Should it be desired to reverse the direction of the coils, the procedure differs only in this respect that the wire is led to the mandrel from below through groove 59.

10 It will be obvious that some changes may be made in the construction of the winder as described by me, without departing from the inventive principle disclosed therein. What I, therefore, wish to claim, is as follows:

15 1. A spring winder of the kind described, comprising a horizontal base, a plate with a window therein, set at an angle to the base in a V-shaped formation, for the reception therein of a transversely disposed mandrel, a sliding bar on said base, parallel to the side thereof, the end of said bar fitting into said window to wedge the mandrel in place, a sliding member affixed to the side of the base, having a vertically adjustable head and a wedge-shaped spacer, projecting beyond the surface of the head into contact with said mandrel, and an elongated feeder to supply the wire to form a spring to said mandrel.

20 2. A spring winder of the kind described, comprising an elongated base, a transverse, inwardly inclined plate at one end thereof, movable means on said base to wedge against said plate, a mandrel transversely disposed with respect to the base, a side member secured to the base in an adjustable longitudinal relation thereto, a wedge-shaped spacer on said member, adjustable perpendicularly and in contact with the mandrel, a grooved feed bar on said base to conduct a wire to the mandrel and means removably affixed to the mandrel to rotate it around its axis and to grasp one end of the wire to be made into a spring.

25 3. A spring winder of the kind described, comprising an elongated base, a plate at one end thereof, inclined inwardly into a V-formation with said plate for reception of a mandrel within the apex of said V-formation, a sliding bar on the base to wedge the mandrel into said apex, means to secure the bar in place, an upright member on the side of the base and disposed at right angle to said inclined plate, a wedge-shaped spacer in a vertically adjustable position on the operative end of said side member, means to shift the member longitudinally with respect to the base, to bring the spacer into abutment with the side of the mandrel, a removable elongated feed bar affixed to said member to conduct a wire to the mandrel, and means to be applied to the mandrel to rotate the same around its axis, and including means to grasp the free end of the wire.

LEONARD R. BUCZKOSKI.
